LETTERING GUIDE

Raymond G. Reed, Oakland, Calif.

Application November 6, 1953, Serial No. 27,466

Term of patent 3½ years

(Cl. D52—1)

Fig. 1 is a front face view of a lettering guide, showing my new design;

Fig. 2 is an end view;

Fig. 3 is a side view; and

Fig. 4 is a back view of my new design.

I claim:

The ornamental design for a lettering guide, as shown.
